Filed Apr. 10, 1961, Ser. No. 64,683

Term of patent 14 years

(Cl. D49—1)

FIG. 1

FIG. 2

FIG. 4

FIG. 3

FIG.5

FIGURE 1 is a front perspective view of a clothes washer embodying our new design;

FIGURE 2 is a cross-sectional view thereof taken on the line 2—2 of FIGURE 1 in the direction of the arrows;

FIGURE 3 is a cross-sectional view thereof taken on the line 3—3 of FIGURE 1 in the direction of the arrows;

FIGURE 4 is a side elevational view thereof; and

FIGURE 5 is a front elevational view thereof.

The broken lines representative of the lower portion of the clothes washer have been omitted in FIGURE 1 for convenience of illustration.

The rear of the clothes washer shown is substantially plain. The dominant features of our design for the clothes washer disclosed reside in the portions shown in

full lines, said portions being characterized by the dual panels as shown.

We claim:

The ornamental design for a clothes washer or similar article, substantially as shown and described.
